UNITED STATES PATENT OFFICE

HENRY F. RICHARDSON, OF NORTHPOR, NEW YORK, ASSIGNOR TO ELEVATOR SUPPLIES COMPANY, INC., OF HOBOKEN, NEW JERSEY, A CORPORATION OF NEW JERSEY

WELL PROTECTION DEVICE FOR ELEVATORS

Application filed September 21, 1928. Serial No. 307,384.

This invention relates to elevators and particularly to means for facilitating the removal of dust and dirt and other refuse which accumulates in elevator cabs.

5 One of the principal objects of the invention is to provide means for preventing the accumulation of such refuse in the pit at the bottom of the elevator shaft. In this connection a feature of the invention is the provision 10 of means for placing a receptacle in the space existing between the elevator and the enclosure walls of the shaft so that when the caretaker sweeps out the elevator cab the refuse will not fall through such space as it usually 15 does to cause an unsightly and possibly dangerous accumulation of refuse at the bottom of the elevator shaft.

Another object of the invention is to provide means for automatically projecting and 20 withdrawing such a receptacle from the location which it occupies during the sweeping operation.

At present when an elevator car is brushed out the dust, etc. is brushed down the space 25 between the car and the door sill and falls to the bottom of the shaft. This, of course, causes a large accumulation of dirt in the pit, which is not only untidy but is a fire hazard from cigarette stubs which may also fall into 30 the pit.

The invention herein disclosed provides means for eliminating this objectionable situation. The advantages to be derived from the use of the invention herein disclosed in 35 addition to those above enumerated will be obvious from a reading of the following description, an understanding of which may be facilitated by reference to the accompanying drawings, wherein;

40 Figure 1 is a view in elevation and partly in section showing a portion of an elevator car in its relation to the opening in the enclosure wall occurring at one of the floors of the building;

45 Figure 2 is an elevation view of the preferred embodiment of the invention as applied to the floor of an elevator car;

Figure 3 is a view in perspective of the parts shown in Figures 1 and 2;

50 Figure 4 is a view of a modified form of the

invention applied to an elevator car shown in its true relation to an opening in the enclosure wall; and

Figure 5 is a view in perspective of the modification shown in Figure 4. 55

Referring to the drawings reference character 1 indicates the floor of an elevator car 2 situated in the enclosure, one wall of which is indicated at 3, the car being shown on a level with one of the floors 4 of the building, 60 said floor being provided with a door 5 guarding the opening to the elevator shaft, the usual sill or threshold occurring at such floor openings being indicated at 6 and the usual threshold on the elevator car being indicated 65 at 7. A pair of brackets 9 and 10 (see Figure 2) are shown attached to the underside of the floor 1 of the elevator car, the brackets having suitable openings therein serving as means for supporting the rod 12, the latter 70 having an extension at one end thereof to which is attached a crank arm 13 rigidly secured thereto by suitable means such as set screw 14. The other end of the crank arm 13 connects with a rod 15 passing up through the floor of the elevator car and having at its upper end a pedal 16, which, when stepped upon, causes the compression of a spring 17 against the collar 18 resting on the floor 1. Between the brackets 9 and 10 is shown a pair of supporting arms 19 and 20 having means at their 75 outer end for the retention of a second rod 21 somewhat similar to the rod 12. These two rods 12 and 21 preferably serve as the means for supporting and attaching any suitable receptacle to be used as the means for catching the refuse swept from the elevator car. As shown in Figures 1, 2 and 3 this receptacle takes the form of a cloth or canvas

80 sack or bag 22, which may be secured to the rods 12 and 21 by any suitable means, such as the hooks 23. With this construction it is apparent that the force of spring 17 will normally hold the rod 15 and hence the crank arm 13 and the arms 19 and 20 in the positions 85 shown in full lines in Figure 1, in which position the receptacle is completely within the vertical projection of the edge of the threshold 7 on the elevator car. This is the position the apparatus normally occupies during 90 95 100

operation of the elevator and by this construction any collision or interference between parts on the elevator car and along the shaftway enclosure is prevented.

5 When the attendant desires to sweep out the elevator it is only necessary for him to step upon the pedal 16, thereby projecting the bag and arms 13 and 19 to the positions indicated in dash lines in Figure 1, in which 10 position the receptacle is in position to catch any refuse swept out of the car.

Figures 4 and 5 show a modified type of receptacle consisting of a tray or trough 25 preferably, though not necessarily, of metal. 15 Such a type of receptacle may be preferred in some cases to the type shown in Figures 1, 2 and 3. As indicated in Figures 4 and 5 the tray 25 may be removed from the arms 30 and 31 simply by lifting the tray from the sockets 20 32 and 33 on the ends of the arms 30 and 31 respectively. This tray 25 is shown as being subject to the same type of control as the sack 22 of Figures 1, 2 and 3, the tray normally occupying the position shown in full 25 lines in Figure 4 and being capable of projection into the dash line position shown upon pressure being applied to the pedal 35.

I wish it to be understood that I do not limit myself to the specific embodiment of 30 the invention disclosed herein, it being obvious that numerous changes may be made in the construction, combination and method of operation of the parts without departing from the scope of this invention as disclosed 35 herein and as defined in the appended claims.

I claim:

1. In combination with a dust collecting receptacle, means for supporting said receptacle beneath the floor of an elevator cab, 40 a spring pressed rod normally serving to maintain said receptacle in such position, and means located in part in the elevator cab for projecting said receptacle into the space existing between the elevator cab and the enclosure wall, said means acting to overcome 45 the normal tendency of said spring pressed rod.

2. Apparatus for use in collecting dust and litter accumulating in elevator cabs comprising 50 a receptacle, means for supporting said receptacle beneath the floor of the cab and out of engagement with the shaft-way walls, and means located in part on the elevator cab for projecting said receptacle into the space 55 between the elevator cab and the shaft-way wall.

3. Apparatus for use in collecting dust and litter accumulating in elevator cabs comprising 60 a receptacle, means for supporting said receptacle beneath the floor of the cab and out of engagement with the shaft-way walls, means located in part on the elevator cab for projecting said receptacle into the space between the elevator cab and the shaft-way 65 wall, and means for returning said receptacle

to its normal position when it is desired to place the elevator in service again.

4. Apparatus for collecting dust and litter accumulating in elevator cabs comprising a receptacle and means for suspending said receptacle across the space between the elevator cab and enclosure wall.

Signed at Hoboken, in the county of Hudson and State of New Jersey, this 12th day of September, A. D. 1928.

HENRY F. RICHARDSON.
